United States Patent Office.

A. H. ALLISON, OF CHARLOTTESVILLE, INDIANA.

Letters Patent No. 61,649, dated January 29, 1867.

IMPROVEMENT IN CULTIVATORS.

The Schedule referred to in these Letters Patent and making part of the same.

TO ALL WHOM IT MAY CONCERN:

Be it known that I, A. H. ALLISON, of Charlottesville, in the county of Hancock, and State of Indiana, have invented a new and useful Improvement in Corn and Cotton Cultivators; and I do hereby declare that the following is a full, clear, and exact description thereof, which will enable others skilled in the art to make and use the same, reference being had to the accompanying drawing, forming a part of this specification, in which—

Figure 1 is a vertical longitudinal section of the carriage, showing a side view of the ploughs and their connections.

Figure 2 is a plan of the corn cultivator of my invention.

Similar letters of reference indicate like parts.

This invention relates to improvements in the construction of machines for the cultivation of Indian corn, cotton, or other plants set in rows in the field; and consists in the arrangement of the ploughs, in connection with the frame, by which they work two sides of one row of corn or cotton at a time, and are completely under the control of the driver, who is seated on the carriage frame, the parts being all simple, strong, and compact.

The truck-frame A is built of strong square timbers, in rectangular form. It is mounted on two driving-wheels, B B, in the usual way. C is a driver's seat, in the rear. E is the draught-pole. D D are plough-beams, on each end of which are placed two standards, a a', one forward of the other, to which are attached the ploughs b b. The fore ends of the plough-beams are suspended by clevises or hooks, c c, to the under side of a cross-bar, d, so that they can swing sidewise, and the rear ends of the beams are hung by hooks or staples, e e, upon suspended ways or metal guide-rods, f f, which are curved outward in conformity with the lateral sweep of the rear ends of the plough-beams, so that the hooks e e can slide on them from one side to the other, for the purpose of allowing the driver to move the ploughs nearer to or further from the corn, as required, which is accomplished by the driver by means of stirrups or levers, g g, fastened on the hind ends of the plough-beams D D. The guide-rods f f are suspended to cross-heads F F, through which the ends pass vertically, and are made adjustable to suit the depth of the ploughs by set-screws h h. The cross-heads F F slide up and down in slots made in uprights, G G G, and they are lowered by means of levers H H, which are fastened to them centrally, the fulcra of which levers are at i i, upon a cross-beam, I, of the truck A, while their free ends extend back on both sides of the driver's seat C, convenient for him to handle. The levers are held down, when the cross-heads F F are depressed, by catch-hooks k k placed on a rear cross-beam, K, and when the levers are released, the cross-heads F F are raised by means of flat curved springs m m, which are attached at one end to the cross-beam I, and at the other free ends bear up against the bottom of the cross-heads F F. On the inside of each of the inside ploughs b b, I place clod-guards, n n, which are little wheels suspended by rods p p to the plough-beams, and made with spokes or open lattice-work of any kind, to allow the finer soil to sift through as they travel alongside of the ploughs when at work, while the larger clods are turned aside and prevented from being thrown upon the young plants.

I am aware that a wheeled cultivator, made to straddle the rows and having a driver's seat, is not new. My claims do not, therefore, have reference thereto.

Having thus described my invention, what I claim as new, and desire to secure by Letters Patent, is—

1. I claim the plough-beams D D, suspended to the curved guide-rods f f, and connected with the stirrups or levers g g, for obtaining lateral movement, in combination therewith, and with the vertically sliding cross-heads F F, the levers H H, and the springs m m, constructed, arranged, and operating substantially as and for the purposes herein described.

2. The arrangement of the rotary perforated clod-guards n n, combined with the ploughs b b, and beams D D, constructed and operating as herein set forth.

A. H. ALLISON.
